UNITED STATES PATENT OFFICE.

JAY W. ROSS, OF FORSYTH, GEORGIA.

SEAL FOR RAILWAY-CAR DOORS.

1,143,441.

Specification of Letters Patent. Patented June 15, 1915.

Application filed February 6, 1915. Serial No. 6,497.

To all whom it may concern:

Be it known that I, JAY W. Ross, citizen of the United States, residing at Forsyth, in the county of Monroe and State of Georgia,

5 have invented certain new and useful Improvements in Seals for Railway-Car Doors; and I do hereby declare the following to be a full, clear, and exact description of the invention, such as will enable others skilled 10 in the art to which it appertains to make and use the same, reference being had to the accompanying drawings, and to letters or figures of reference marked thereon, which form a part of this specification.

15 This invention relates to seals and more particularly to that class of such devices especially adapted for use with railway car doors and has for its primary object the provision of a seal which may be effectively 20 locked without the use of a seal press or other tool.

A further object of this invention is to construct a seal of the character set forth out of sheet metal, thus lowering the cost of 25 manufacture of the device.

A further object of the invention is to provide automatic locking means adapted to receive the shackle and securely lock the same.

30 With the foregoing and other objects in view, this invention consists in the peculiar combination and arrangement of the various related elements of a seal as herein-after described and more particularly set 35 forth in the appended claims.

Referring to the drawings forming a portion of this specification and illustrating the preferred embodiment of the invention, similar reference numerals indicating similar 40 parts wherever used: Figure 1 is a perspective view of the seal. Fig. 2 is an enlarged section showing the seal locked. Fig. 3 is a perspective view of the locking members. Fig. 4 is a detail perspective 45 view showing the locking members. Fig. 5 is a section on the line 5—5 of Fig. 2.

The seal is represented as a whole by the numeral 7, and comprises a long narrow strip bent at 8', to form two portions 8 and 50 9, comprising the shackle and having a portion 10, bent back to form a head 11, which is provided with an opening 12. The portion 8, extends from a wider portion 13, having upwardly extending side members 55 14 and 15. A relatively smaller portion 16 extends from the portion 8, and carries a

strip 17, of the same width as the portion 8. The strip 17 is provided with side members 18 and 19 bent at right angles thereto. A strip 20, extends from the portion 17, and is bent back upon itself at 21, for a purpose hereinafter set forth.

60 The locking mechanism comprises a V-shaped metal strip 23, one leg of which is doubled back upon itself and pointed to form a tongue 26. This leg of the V-shaped strip has at approximately its center a struck up portion 24 to form a second tongue. The tongue 24 is struck up on the same side as the tongue 26 and therefore 65 lies directly beneath it. The opposite side of the member 23, has a central aperture 28, therein, and upon either side thereof is a small projection 29 forming guides.

70 The method of assembling the seal is as follows: The end 30 of the V-shaped locking plate 23 is inserted under the portion 21 of the strip 20, and crimped or riveted in place. The strip 20 is then bent until the portion 31, of the locking plate 23, lies on 75 the inner face of the strip 17 as shown in Fig. 2. The strip 17, is then bent in the same direction until the strip 20 abuts against the portion 8. The side members 14 and 15, of the portion 8, and the side 80 members 18 and 19, of the portion 17, will now be adjacent one another, where they may be crimped or bent together in any suitable manner, as at 32.

85 In order to lock the seal, the head 11, is 90 inserted underneath the strip 20, the spring metal allowing of ready insertion by compressing the head 11. As soon as the head 11 is free of the strip 20, the head 11 will expand. A slight forward pull upon the 95 shackle 9 will cause the head 11, to travel into the V-shaped strip 23, and under the tongue 26. When the movement of the head is reversed the guides 29 will cause the free end of the tongue 26 to engage the hole 12, 100 and upon a continued reverse movement the free end of the head springs under and behind the tongue 24. When the parts are in this position, the tongue 24 prevents forward movement of the head, while the tongue 26, 105 holds said head against rearward movement, thus locking the head in the housing. In order to make the locking action secure, the free end of the tongue 26 springs into the central aperture 28, between the projections 110 29, of the plate 23. Obviously when the head is in locked position, forward move-

ment is prevented by the tongue 24, and rearward movement by the tongue 26. Once the seal is locked, it is practically impossible to pick it, and the only way to release the parts is to destroy the casing or cut the members 8 or 9. If one tries to force a tool or the like into the housing to release the lock, it is evident that the attempt will be foiled on account of the disposition of the members 20 and 23.

I realize that considerable variation of the specific details may be resorted to without departing from the spirit of this invention, and it is therefore not my intention to limit myself to the specific form herein shown and described, but to construe the following claims as broadly as the state of the prior art will permit.

What I claim as new and desire to secure by Letters Patent, is:—

1. A seal comprising a chamber and a shackle having one end attached thereto, locking means in said chamber, said means comprising a V-shaped plate, oppositely extending and overlying tongues on one of the legs of the said plate, the other leg of the said V-shaped plate having an opening to receive one of the said tongues, the free end of the shackle having an opening therein to coöperate with the said tongues upon insertion thereunder.

2. A seal comprising a chamber and a shackle, locking means in said chamber adapted to hold said shackle, said locking means comprising a V-shaped plate, two tongues carried by one leg of the said plate, both tongues on the inside of the said leg, one of the said tongues longer than the other and overlying the shorter tongue, one end

of the shackle having an opening to coöperate with the said tongues upon insertion thereunder and means carried by the other leg of the said V-shaped plate for guiding the end of the shackle so that it will be engaged by the said tongues.

3. A seal comprising a chamber and a shackle having one end attached thereto, locking means within the said chambers, said locking means comprising a V-shaped plate, one leg of the said plate fastened to the said chamber and the other leg free, one end of the free leg of the plate bent back inside upon itself to form a tongue, the said leg having a central struck-out portion on the inside thereof, forming a second tongue, the said struck-out portion being on the same side of the free leg as the first-mentioned tongue and lying beneath it, projections on the other leg of the V-shaped plate forming guides, the said leg having a central opening between the guides to receive the innermost tongue, the free end of the shackle bent back upon itself and having an opening in the bent portion thereof, the opening in the free end of the shackle coöoperating with one of the tongues carried by the locking means, the end of the said shackle coöperating with the other tongue, the said guides directing the bent end of the shackle so that it will be engaged by the tongues.

In testimony whereof I have signed my name to this specification in the presence of two subscribing witnesses.

JAY W. ROSS.
